UNITED STATES PATENT OFFICE.

CHARLES J. MADONNA, OF NEW YORK, N. Y.

DRIP-RECEPACLE FOR UMBRELLAS.

1,110,215.

Specification of Letters Patent.

Patented Sept. 8, 1914.

Application filed December 13, 1913. Serial No. 806,510.

To all whom it may concern:

Be it known that I, CHARLES J. MADONNA, a citizen of the United States, and a resident of the city of New York, borough of Brooklyn, in the county of Kings and State of New York, have invented a new and Improved Drip-Receiptacle for Umbrellas, of which the following is a full, clear, and exact description.

An object of the invention is to provide a new and improved drip receptacle for umbrellas arranged to receive and retain the water flowing down the covering of an umbrella at the time the latter is stood up or hung on a rack, thus preventing the drip water from flowing onto and soiling the floor. Another object is to provide a simple device which can be readily placed in position on the terminal of the umbrella stick or can be removed therefrom, and when in position on the stick terminal can be readily folded to take up very little room and without forming an unsightly attachment. In order to accomplish the desired result use is made of a cup having an attaching hub adapted to engage the terminal of the umbrella stick to hold the drip receptacle in place, a collar for the passage of the said terminal and a tubular covering attached at its ends to the said cup and the said collar.

A practical embodiment of the invention is represented in the accompanying drawings forming a part of this specification, in which similar characters of reference indicate corresponding parts in all the views.

Figure 1 is a sectional side elevation of the drip receptacle as applied to an umbrella in extended position for the reception of the drip water; Fig. 2 is a plan view of the drip receptacle; Fig. 3 is a side elevation of the drip receptacle as applied and in folded position; Fig. 4 is a sectional side elevation of a modified form of the drip receptacle as applied and in extended position for the reception of the drip water; Fig. 5 is a side elevation of the same in folded position; Fig. 6 is a sectional plan view of the same on the line 6-6 of Fig. 4; and Fig. 7 is a similar view of the same on the line 7-7 of Fig. 4.

A cup A, preferably made of metal, is provided at its bottom with a hub B provided interiorly with a ring C, of rubber or other suitable elastic material, to clampingly engage the terminal of the stick D of the umbrella, as plainly indicated in Fig. 1.

The cup A is provided intermediate the hub B and the top of the cup with an annular recess E into which fits one end of a tubular covering F, preferably of rubber or other suitable flexible or elastic material. The other end of the covering F fits into an annular recess G formed exteriorly in a collar G provided interiorly with a ring H, of rubber or other similar material, for clampingly engaging the terminal of the stick D near the outer end thereof. The cup A is provided intermediate the hub B and the recess E with apertures I to allow water to pass from the cup A into the drip receptacle.

In order to use the drip receptacle the operator slips the device into position on the terminal of the stick D, as plainly indicated in Fig. 1, so that the cup A is adjacent the crown of the umbrella while the collar G is located near the terminal of the stick D. Now any water that flows down the covering of the umbrella passes into the cup A and flows from the latter through the openings I into the receptacle formed by the covering F and collar G around the terminal of the stick D so that the water accumulates in the said receptacle and is thus prevented from flowing onto a floor or other surface. After the umbrella is dry it is tilted into an approximately horizontal position to allow the water contained in the receptacle to flow out of the same by way of the apertures I and the cup A into a spittoon, sink or other receptacle, for the drip water. If desired, the receptacle after being filled may be slipped off the terminal of the stick D and its contents drained into a suitable receptacle.

Instead of removing the drip receptacle from the umbrella and replacing it thereon for use after rain, the said drip receptacle may be permanently left in position on the umbrella, and by slightly turning the umbrella while holding the collar G the covering F may be twisted into folded position, as shown in Fig. 3, so that the drip receptacle does not form an unsightly attachment on the umbrella.

In the modified form shown in Figs. 4, 5, 6 and 7, the cup J is provided with a hub J' and apertures J², and the cup J' is also provided with an interior retaining ring K, similar to the ring C previously mentioned, and from the ring K extends a sleeve L through which passes the terminal of the

stick D' of the umbrella. On the cup J is secured one end of the covering N attached at its other end to a collar O mounted to slide on the sleeve L and limited in its outward movement thereon by a stop flange formed on the outer end of the sleeve L. The collar C is provided with a ring P, of rubber or other material, and also with flat springs Q adapted to bear at their ends 10 on the exterior surface of the sleeve L to hold the collar O in position on the sleeve L into which it is moved by the operator. The collar O is connected by a number of flat curved springs R with the cup J so as 15 to hold the covering N in extended position at the time the collar O is moved upward on the sleeve L into the position shown in Fig. 4. It will be noticed that in this case water passes into the receptacle by way 20 of the cup J the same as above described, and the water can be drained out of the receptacle in the same manner as previously mentioned. When the receptacle is not used for receiving the drip water the operator 25 slides the collar O outward until it abuts against the stop collar L', and in doing so the springs R are relaxed to allow a relaxing of the covering N, as shown in Fig. 5, thereby holding the covering in a folded 30 position without forming an unsightly attachment to the umbrella.

The drip receptacle shown and described is very simple and durable in construction and can be readily placed in position on the 35 umbrella stick or removed therefrom whenever it is desired to do so.

Having thus described my invention, I claim as new and desire to secure by Letters Patent:

40 1. A drip receptacle for umbrellas, comprising a cup having an exterior annular

recess and provided with an attaching hub at its bottom, and apertures in the said bottom and leading to the exterior of the hub, clamping means in the said hub for clamping 45 the umbrella stick, a collar having an exterior annular recess and clamping means on the inside for engaging the umbrella stick, and a tubular covering attached at one end in the recess of the said cup and at the other end in the recess of the 50 said collar.

2. A drip receptacle for umbrellas, comprising a cup having a hub and apertures in its bottom leading to the exterior of the hub, clamping means in the hub for engaging 55 the umbrella stick, a collar having clamping means on its interior, springs connecting the cup with the collars, and a tubular covering of flexible material secured 60 to the cup and collar.

3. A drip receptacle for umbrellas, comprising a cup having an attaching hub at its bottom, and apertures in the said bottom and leading to the exterior of the hub, 65 clamping means in the said hub for engaging the umbrella stick, a sleeve held on the said hub, a collar slidably engaging the said sleeve and provided with interior clamping means engaging the sleeve to hold 70 the collar in any position on the sleeve, flat springs connecting the said cup with the said collar, and a tubular covering of flexible material attached to the said cup and collar and stretched over the said springs. 75

In testimony, whereof I have signed my name to this specification in the presence of two subscribing witnesses.

CHARLES J. MADONNA.
